SICK BED DRAINAGE BAG

John Brenner, 2209 N. Freeman St., Santa Ana, and Harley W. Burr, Santa Ana, Calif.; said Burr assignor to said Brenner

Filed Aug. 26, 1963, Ser. No. 76,359

Term of patent 14 years

(Cl. D83—1)

The broken line showing of a drainage tube and fluid material are shown for illustrative purposes only.

We claim:

The ornamental design for a sick bed drainage bag, substantially as shown and described.
